(57) **CLAIM**

The ornamental design for a double capsule pop-up memo dispenser, as shown and described.

DESCRIPTION

FIG. 1 is a front view of double capsule pop-up memo dispenser showing my new design;

FIG. 2 is a rear view thereof;

FIG. 3 is a left side view thereof;

FIG. 4 is a right side view thereof;

FIG. 5 is a top view thereof;

FIG. 6 is a bottom view thereof; and,

FIG. 7 is a perspective view thereof.

The broken lines showing environment in FIGS. 1 and 7 are for information purposes only and form no part of the claimed design.
